UNITED STATES PATENT OFFICE.

GEORGE R. ROGERS, OF CRAWFORDSVILLE, INDIANA, ASSIGNOR OF ONE-
THIRD TO SAMUEL SCOTT AND ONE-THIRD TO GEORGE LITTLE, OF
CRAWFORDSVILLE, INDIANA.

GATE.

No. 823,293.

Specification of Letters Patent.

Patented June 12, 1906.

Application filed March 19, 1906. Serial No. 306,855.

To all whom it may concern:

Be it known that I, GEORGE R. ROGERS, a citizen of the United States, residing at Crawfordsville, in the county of Montgomery and State of Indiana, have invented certain new and useful Improvements in Gates; and I do declare the following to be a full, clear, and exact description of the invention, such as will enable others skilled in the art to 5 to which it appertains to make and use the same.

This invention relates to improvements in gates.

The object of the invention is to provide a 15 gate which may be readily unlatched and opened by the occupant of a vehicle approaching the same.

A further object is to provide a gate of this character having an operating mechanism 20 which will be simple, strong, and durable in construction, efficient in operation, and which will not be affected by snow and ice.

With the above and other objects in view the invention consists of certain novel features of construction, combination, and arrangement of parts, as will be hereinafter described and claimed.

In the accompanying drawings, Figure 1 is a 30 perspective view of the gate looking toward one side of the same and showing the gate in closed position, parts of the gate being broken away to illustrate the construction of the latch mechanism. Fig. 2 is a similar view looking toward the opposite side 35 of the gate and showing the same in open position. Fig. 3 is a plan view of the hinge-post and a portion of the gate, showing the arrangement of the operating mechanism; and Fig. 4 is a detail horizontal sectional 40 view through the latch-post and a portion of the gate, taken immediately above the latch-bar.

Referring more particularly to the drawings, 1 denotes the gate, which may be of any 45 suitable construction, but which is here shown as constructed of wood and consisting of a series of parallel longitudinally-disposed bars 2, which are connected by vertically-disposed end cross-bars 3 and an intermediate cross-bar 4, said bars of the gate being braced by means of inclined brace-bars 5, which are arranged between the upper end of the intermediate bar 4 and the end cross-bar 3.

The gate 1 is hingedly mounted at one end upon a hinge-post 6 and is adapted to engage a latch-post 7 when in closed position and a latch-post 8 when in open position. Said latch-posts are provided with suitable keepers 9, with which the outer end of a latch-bar 10 is adapted to be engaged. This latch-bar 60 55 is preferably formed from one of the longitudinally-disposed bars of the gate, said bar being loosely mounted in the cross-bars 3 and 4 and connected at its inner end to the adjacent longitudinal bar above the same by 65 means of parallel obliquely-disposed hanger-bars 12. The outer end of the latch-bar 10 is provided with a longitudinally-disposed slot 13, through which is passed a supporting-bolt 14, whereby said outer end of the latch-bar 70 75 is slidably connected with the outer cross-bars of the gate. The outer end of the latch-bar projects beyond the outer cross-bars of the gate, said projecting end of the latch-bar being adapted to engage a beveled latch-plate 15, forming a part of the keepers 9 of the latch-posts 7 and 8, whereby when said gate is swung to an opened or closed position the same will be automatically locked in said 80 position.

In order that the gate may be opened by the occupant of a vehicle, a suitable operating mechanism is provided, said mechanism consisting of a vertically-disposed operating-lever 16, which is pivotally connected at its 85 lower end to a post or block set in the ground, said lever being provided adjacent to its lower end with a right-angularly-disposed bail or loop-shaped arm 17, which is adapted to engage a right-angularly-disposed crank-pin 18, formed on or rigidly secured to an operating-rod 19, which is mounted in suitable bearing-brackets 20, secured to the hinge-post 6 and the block or post of the operating-lever, as shown. The length of the rod 19 is 95 such that the operating-lever may be placed at a considerable distance from the gate. On the end of the operating-rod adjacent to the hinge-post 6 and on the opposite side of the same from the operating-lever 15 is secured 100 an upwardly-projecting obliquely-disposed arm or bar 21, to the upper end of which is loosely connected a link 22. The opposite end of the link 22 is loosely connected with a laterally-projecting right-angularly-formed 105 gate-lever 23, said gate-lever being pivotally

connected at its opposite end to one of the longitudinally-disposed gate-bars 2 and preferably to the gate-bar immediately below and adjacent to the bar 10.

- 5 To the gate-lever 23, adjacent to the connection of the link 22, is secured one end of a short chain or other flexible connection 24, the opposite end of which is connected to the latch-bar 10, whereby when the gate-lever is 10 operated to open the gate the chain 24 will be drawn upon to move the said latch-bar 10 back a sufficient distance to disengage the projecting end of the same from the keeper of the latch-post. A further movement of 15 the operating mechanism will swing the gate to an open position and into engagement with the latch-post 7. By forming the gate-lever as herein shown and described and providing suitably - arranged stops, which are here 20 shown and are preferably in the form of upwardly-projecting bars 25, secured to the longitudinal bar of the gate, a limited initial movement will be allowed said gate-lever, thereby permitting the chain 24 to be drawn 25 upon and the latch-bar operated before any pull is applied to the gate by the operating mechanism.

After the gate has been swung to an open position and into engagement with the latch-post 7 the operating mechanism is released, which will permit the latch-bar to automatically engage the keeper in said latch-post 7. Said latch-bar being supported at its inner end by inclined hanger-bars 12 will by reason of its own weight slide forwardly or outwardly, thus projecting the outer end into the keeper of the latch-post and automatically locking the gate in an open or closed position.

30 40 From the foregoing description, taken in connection with the accompanying drawings, the construction and operation of the invention will be readily understood without requiring a more extended explanation.

45 Various changes in the form, proportion, and the minor details of construction may be resorted to without departing from the principle or sacrificing any of the advantages of this invention.

50 Having thus described my invention, what I claim as new, and desire to secure by Letters Patent, is—

1. The combination with a swinging gate, of latch-posts adapted to hold said gate in its 55 opened or closed position, a slidably-mounted latch-bar arranged in said gate to engage keepers in said latch-posts, a right-angularly-formed gate-lever pivotally mounted on said gate, stop-lugs adapted to limit the pivotal

movement of said gate-lever, an oscillatory operating-rod, a right-angularly-projecting arm fixed on one end of said rod and a crank-arm arranged on the opposite end of the same, a pivotally-mounted operating-lever, means to loosely connect said operating-lever with 60 said crank-arm, a link to connect said right-angularly-projecting arm with said gate-lever, and means to connect said gate-lever with said latch-bar, substantially as described.

2. The combination with a swinging gate, 70 of latch-posts adapted to hold said gate in its opened or closed position, a slidably-mounted latch-bar arranged in said gate to engage keepers in said latch-posts, a right-angularly-formed gate-lever pivotally mounted on said 75 gate, stop-lugs adapted to limit the pivotal movement of said gate-lever, an oscillatory operating-rod, a right-angularly-projecting arm fixed on one end of said rod and a crank-arm arranged on the opposite end of the same, 80 a pivotally-mounted operating-lever, means to loosely connect said operating-lever with said crank-arm, a link to connect said right-angularly-projecting arm with said gate-lever, a flexible connection between said gate-lever and latch-bar and means whereby said latch-bar is supported to cause the same to automatically engage said keepers in said 85 latch-posts, substantially as described.

3. The combination with a swinging gate, 90 of latch-posts adapted to hold said gate in its opened or closed position, a slidably-mounted latch-bar arranged in said gate to engage keepers in said latch-posts, a right-angularly-formed gate-lever pivotally mounted on said 95 gate, stop-lugs adapted to limit the pivotal movement of said gate-lever, an oscillatory operating-rod, a right-angularly-projecting arm fixed on one end of said rod and a crank-arm arranged on the opposite end of the same, 100 a pivotally-mounted operating-lever, means to loosely connect said operating-lever with said crank-arm, a link to connect said right-angularly-projecting arm with said gate-lever, a chain to connect said gate-lever with 105 said latch-bar, obliquely-disposed hanger-bars adapted to support the inner end of said latch-bar and a bolt arranged in said gate to engage a slot in the outer end of said latch-bar thereby slidably supporting this end of 110 the same, substantially as described.

In testimony whereof I have hereunto set my hand in presence of two subscribing witnesses.

GEORGE R. ROGERS.
